Glass Design Pat.

PATENTED FEB 1 1870

2834

D. B. Hickley: Design for Stems of Articles of Glassware.

United States Patent Office.

DANIEL C. RIPLEY, OF BIRMINGHAM, PENNSYLVANIA.

Design No. 3,834, dated February 1, 1870.

DESIGN FOR STEMS FOR GLASS-WARE.

The Schedule referred to in these Letters Patent and making part of the same.

To all whom it may concern:

Be it known that I, DANIEL C. RIPLEY, of Birmingham borough, in the county of Allegheny, and State of Pennsylvania, have invented a new and useful Design for Stems or Bases of Articles of Glass-Ware; and I do hereby declare the following to be a full, clear, and exact description thereof, reference being had to the accompanying drawing, making a part of this specification, in which—

Figure 1 is a side elevation of a lamp-foot, showing my improved design for the stems of articles of glass-ware, and

Figure 2 is a cross-section thereof through the lines $x-x$, fig. 1.

Like letters of reference indicate like parts in each.

My improved design for bases or stems for articles of glass-ware consists of a double stem, united by a thin web.

To enable others skilled in the art to make and use my improved design, I will proceed to describe the same, with particular reference to a glass lamp-foot or stem.

The foot b is of any desired shape or conformation. From a point at or near its upper end, a pair of branching stems, $a a$, arise, in regular or irregular form, and unite in, or at, or near the socket of the candlestick, or

the peg c , or the bowl of the lamp, or other receptacle arranged thereon.

The mould in which the branching stems $a a$ are formed, has a cavity, properly shaped, for forming a thin web, d , which connects the side branching stems $a a$, and, with them, forms a single stem. On this web d , any desired ornamental design may be pressed, cut, or engraved.

By making stems of this form, I am enabled to facilitate materially the manufacture of them, since I can remove the articles from the mould before the side stems are fully solidified.

The web d , being comparatively thin, solidifies almost instantly, and itself then possesses sufficient strength to hold the semi-plastic side stems $a a$ in shape, while cooling and solidifying.

What I claim as my invention, and desire to secure by Letters Patent, is—

The improved design for stems for glass-ware, consisting of side stems $a a$, united by a thin solid web, d , substantially as shown and described.

In testimony whereof, I, the said DANIEL C. RIPLEY, have hereunto set my hand.

Witnesses: DANIEL C. RIPLEY.
A. S. NICHOLSON,
G. H. CHRISTY.
